UNITED STATES PATENT OFFICE.

JOHN M. AHLGREN, OF INDIANAPOLIS, INDIANA, ASSIGNOR TO AHLBELL BATTERY CONTAINER CORPORATION, OF WAUKEGAN, ILLINOIS, A CORPORATION OF ILLINOIS.

ART OF MANUFACTURING CONTAINERS.

Application filed April 28, 1922. Serial No. 557,131.

To all whom it may concern:

Be it known that I, JOHN M. AHLGREN, a citizen of the United States, residing at Indianapolis, in the county of Marion and State of Indiana, have invented a new and useful Improvement in the Art of Manufacturing Containers, of which the following is a specification.

My invention relates more particularly, though not exclusively, to the manufacture of battery containers commonly of a form and construction to receive the battery elements of a plural cell battery, as for example, and more particularly, storage batteries such as are used in automobiles and which containers are, by preference, formed of any suitable rubber compound.

My objects are to reduce the cost of manufacture of such containers and more especially containers of the type wherein the bottom, side walls and partitions dividing the container into cells are integral with each other; to improve upon containers as hitherto provided; to produce a highly satisfactory and durable construction thereof; to provide a container wherein the handle portions thereof are formed integral with the walls on which they are provided and preferably outwardly offset from the walls carrying them; and other objects as will be manifest from the following description.

Referring to the accompanying drawings:

Figure 1 is a perspective view, with the parts disassembled, but in relatively alining position, of a core-equipped vulcanizing mold structure involving features of my invention. Figure 2 is a similar view of the various elements from which the container may be formed in the mold shown in Fig. 1. Figure 3 is a perspective view of the completed container, with portions thereof broken away to disclose interior details. Figure 4 is a plan view of the bottom, core-equipped, plate of the mold, one of the sections of the core being shown in section. Figure 5 is a broken, vertical, sectional view taken through the mold and showing the parts illustrated in Fig. 1, in assembled position, but with the container-forming elements omitted, the section being taken at the line 5 on Fig. 4 and viewed in the direction of the arrow. Figure 6 is a vertical sectional view of the structure shown in

Fig. 4, this section being taken at the line 6 on Fig. 4 and viewed in the direction of the arrow. Figure 7 is a view like Fig. 6 of the upper right-hand corner of the structure shown in this figure, this view showing the adjacent portion of the container formed therein and illustrating the position occupied by the excess container-forming material in the molding of the material to form the container. Figure 8 is a view in side elevation of the plate to which the cores are connected, but with the cores omitted, one-half of the view being in section with the core plate for the handle at this end of the mold omitted; and Figure 9, a perspective view of the core plate for the handle portion of the container.

The construction of mold illustrated, comprises a bottom plate 21 from which rises, centrally thereof, the core-structure about which the elements shown in Fig. 2, and hereinafter referred to, are molded. The core-structure shown, and suitable for molding a 3-cell container, is formed of three similar sections 22 extending cross-wise of the plate 21 and extending at their lower ends into recesses 23 extending transversely of the upper, relatively narrow, portion 24 of the plate 21, these core-sections being thus spaced apart as represented at 25. The core-sections 22 are secured to the plate as by the bolts 26 and are preferably of the same length as the recesses into which they extend. The opposite walls of the sections 22 converge slightly in an upward direction in Fig. 1 for the purpose of providing draft and their upper surfaces contain series of alining notches 27 the opposite walls of which converge downwardly, likewise to provide draft. By locating the core elements 22 as stated, the plate portion 21 extends laterally in all directions beyond these core sections and in a plane below the latter, thereby affording the continuous ledge 28 surrounding the group of core-sections 22. The plate 21 at opposite edges thereof adjacent the narrow ends of the core-sections 22 is provided with bars 29 which rest upon certain portions of the ledge 28 and are secured, as by screws 30, in position to overlap the lower edges of the ends of the core-sections 22 and aid in preventing displacement of the latter. The

portions of the ledge 28 at the ends of the plate 21 are recessed, as represented at 31, to receive core-plates 32 hereinafter described, and beyond these recesses are recessed at 33 for a purpose hereinafter described. The core-plates 32, shown as recessed as represented at 34, at their outer ends, to interfit with the ends of the bars 29 vertically slidingly fit within the recesses 31 and between their ends present the laterally-opening channels 35 of general U-shape which open at their ends through the upper surfaces of the core-plates 32 and in which the handle-portions of the container are formed, the recesses 33 having curved lower surfaces substantially concentric with the lower surfaces of the channels 35 but in a lower plane as shown.

The ledges provided by the upper surfaces 20 of the bars 29 and the surfaces provided by the tops of the core-plates 32 constitute the bottom surfaces of the mold cavity, for the portions of the container located between the handle portions thereof, and the channels 25 constitute the mold cavities for the handle-portions. The ledges 28 serve as supports for the side and end walls hereinafter referred to, of the mold.

In the use of the mold structure for producing a container, the container-forming material located in the mold and preferably assembled with the core, as hereinafter stated, is subjected to vulcanizing heat, and to this end the core sections 22 of the mold structure, which latter is preferably made of metal, are chambered, as represented at 36, to receive the medium, as for example steam, for effecting the vulcanizing operation. In the arrangement shown the bottom plate 21 of the mold contains a plurality of passages 37 and 38 opening into the respective chambers 36 and serving as a means for circulating steam through these chambers.

45 The side-and-end-wall-forming portion of the mold is represented at 39, it being shown as a hollow rectangular structure open at its top and bottom and adapted to be applied to seating position at its lower edges upon the ledge 28 to encircle the core-structure formed of the sections 22 and provide, between this core-structure and the structure 39, a continuous space, the wall-forming portion 39 of the mold relatively closely fitting the vertical exterior surfaces of the bars 29 and the core-plates 32. The edges of the end-wall-forming portions of the structure 39 shown as lowermost in Fig. 1, are provided with depending portion 40 which, in the assembly of the structure 39 with the core-equipped lower plate 21, extend into, and conformingly fit, the recesses 33. The inner surfaces of the wall portions of the member 39 extending adjacent to the core-plates 32 are recessed at their lower edge portions, as

represented at 39* to provide for the molding of a sufficient body of the container-forming material at the juncture of the handle-portions of the container with the walls carrying them.

70 The mold-member 39 extends above the top surfaces of the core sections 22, and contains dowel-receiving openings 41 to receive the depending dowels 42 provided on the top plate 43 of the mold. This plate is provided with a depending rectangular portion 44 inset from the marginal edges of the plate 43 throughout their extent and of such shape and proportions that it extends into the upper end of the opening in the structure 39, but in spaced relation thereto throughout its extent, to provide the continuous clearance represented at 45, the parts being so proportioned and arranged that a space is provided between the upper surfaces of the core sections 22 and the under surface of the depending portion 44 of the plate 43.

75 The material from which the container is to be formed may be of any suitable character and introduced into the mold cavity in any suitable form, but, in the production of plural cell battery construction, as, for example, for current storage purposes, it is preferably formed of any suitable rubber compound capable of resisting the action of the acid used in storage batteries and vulcanizable into the desired hard condition, such rubber compounds being commonly known in the art, and it is preferably provided in the form of a plurality of elements, the greater portion of which are of sheet form. The elements referred to and as shown more particularly in Fig. 2 and 80 preferably employed, comprise the opposite side-wall-forming sheets 11, the end-wall-and-handle-forming sheets shown as each formed of the plane section 12, and the apertured sheet-section 13, the partition-forming sheets 14 and 15, the bottom-forming sheet 16, and the rib-forming strips 17. The 85 various elements illustrated in Fig. 2 are shown in inverted condition, compared with the position they occupy in the finished container illustrated in Fig. 3, as the container is illustrated in the drawings as being molded in inverted condition. The edges of the sheets 14 and 15, shown uppermost in Fig. 2, contain series of notches 18, the walls of which converge downwardly, to receive the 90 rib-forming elements 17, the side walls of which converge downwardly, the elements 17 extending crosswise of the sheets 12, 14 and 15 and abutting at their ends the inner faces of the sheets 12. The edges of the elements 13 shown lowermost in Fig. 2, are 95 provided with depending portions 19 which, in the finished structure, extend above the plane of the upper edges of the side walls 11 and the partitions 14 and 15, and are outwardly offset from the walls 12, the portions

100 105 110 115 120 125 130

The material from which the container is to be formed may be of any suitable character and introduced into the mold cavity in any suitable form, but, in the production of plural cell battery construction, as, for example, for current storage purposes, it is preferably formed of any suitable rubber compound capable of resisting the action of the acid used in storage batteries and vulcanizable into the desired hard condition, such rubber compounds being commonly known in the art, and it is preferably provided in the form of a plurality of elements, the greater portion of which are of sheet form. The elements referred to and as shown more particularly in Fig. 2 and 80 preferably employed, comprise the opposite side-wall-forming sheets 11, the end-wall-and-handle-forming sheets shown as each formed of the plane section 12, and the apertured sheet-section 13, the partition-forming sheets 14 and 15, the bottom-forming sheet 16, and the rib-forming strips 17. The 85 various elements illustrated in Fig. 2 are shown in inverted condition, compared with the position they occupy in the finished container illustrated in Fig. 3, as the container is illustrated in the drawings as being molded in inverted condition. The edges of the sheets 14 and 15, shown uppermost in Fig. 2, contain series of notches 18, the walls of which converge downwardly, to receive the rib-forming elements 17, the side walls of which converge downwardly, the elements 17 extending crosswise of the sheets 12, 14 and 15 and abutting at their ends the inner faces of the sheets 12. The edges of the elements 13 shown lowermost in Fig. 2, are 90 provided with depending portions 19 which, in the finished structure, extend above the plane of the upper edges of the side walls 11 and the partitions 14 and 15, and are outwardly offset from the walls 12, the portions

19 containing openings 20 therein to form finger grips by means of which the finished battery may be conveniently handled.

- In forming a container the various elements shown in Fig. 2, preferably heated before being applied to the mold to render the rubber compound of putty-like consistency, are assembled with the core as follows: The partition-forming sheets 14 and 15 are 10 inserted into the spaces 25 to rest at their lower edges on the portion of the plate 21 beneath them, the notches 18 registering with the notches 27 in this position of the sheets 14 and 15 and the elements 17 then 15 introduced into the notches 18 and 27; the elements 13 are then applied to the core-plates 32 to cause the portions 19 to extend into the channels 35 and the assembled core-plates 32 and elements 13 applied to 20 position on the core-plate 21, the plates 32 being positioned as shown in Fig. 1; the sheets 12 are then applied to the outer end surfaces of the two outermost core sections 22 to extend at their lower edges upon the 25 tops of the core-plates 32 and into the spaces between the core-sections 22 and the elements 13, the upper surfaces of the strips 17 extending substantially flush with the upper edges of the sheets 12, 14 and 15; the 30 sheets 11 are then applied to the opposed remaining sides of the core-structure to rest upon the bars 29, and preferably completely overlap the end edges of the sheets 12; and the sheet 16 then applied to the upper edges 35 of the other elements applied to the core-structure as stated, in which position it extends into the space provided between the upper ends of the core sections 22 and the under surface of the depending portion 44 40 of the plate 43, the sheet 16 being of such dimensions that it will, by preference, extend substantially flush with the outer surfaces of the elements 11 and 12.

- The mold structure 39 is then applied to 45 the plate 21 to surround the container-forming elements applied to the core-structure as stated, the structure 39 seating at its lower edge upon the ledge 28 and its depending portions 40 extending into the recesses 33. 50 The top plate 42 is then applied to the top of the structure 39.

It may be here stated that the amount of container-forming material introduced into the mold, or in other words the amount of this material forming the elements shown 55 in Fig. 2, is sufficiently in excess of the amount of the material contained in the finished container, this excess being preferably provided in the upper sheet 16, that the container-forming material, when subjected to the operations hereinafter described, will be caused to completely fill the mold cavities provided and permit of the material being subjected to the desired compressive stresses.

60 In accordance with the preferred manner

of using the mold structures, the contents of the mold, in plastic condition as stated, are subjected to relatively great pressure by any suitable means for the purpose of forcing the top plate 43 with great force 70 toward the bottom plate 21, it being preferred that a force of substantially three-fourths of a ton per square inch be applied, with the result that the container-forming plastic material is forced with great pressure 75 into all portions of the mold cavities, thereby firmly bonding contiguous marginal, and edge, portions of the various elements shown in Fig. 2. The mold is then placed in a hydraulic vulcanizer which, by 80 preference, exerts the same force as that above stated against the top plate 43 and the plate 21, the steam in the vulcanizer circulating through the chambers 36 in the core-sections 22, by reason of the provision 85 of the passages 37 and 38, the mold remaining in the vulcanizer until the container-forming material has become vulcanized to the desired degree, in which operations above stated, the various elements of Fig. 90 2 are caused to become united at their contiguous marginal portions and edges, into a substantially homogeneous structure and vulcanized to produce the integral container 95 shown in Fig. 3.

After the mold and its contents have been subjected to the vulcanizing heat for the desired length of time the mold and its contents are preferably cooled, as for example by filling the hydraulic vulcanizer with 100 cooling water, in place of the steam, and the mold and its contents cooled off while maintaining the pressure stated, against the mold-plates.

In the subjection of the contents of the 105 mold to the high pressure as stated, the excess material is forced upwardly into and through the clearance 45 and into the substantially horizontal space between the upper edges of the structure 39 and the under side of the plate 43 at its marginal portions, as represented more clearly in Fig. 7.

After cooling the formed container it is removed from the mold preferably by first 110 removing the top-plate 43 following which 115 the fin formed of the excess material referred to and represented at 46 is preferably removed as, for example, by running a knife around the lower edge of this fin where it connects with the main portion of the mold-120 ed container, and the portion 39 of the mold, the opposed inner side walls of which preferably converge slightly upwardly, then lifted off the core-equipped plate 21, which leaves the formed container free to be 125 stripped from the core-equipped plate 21 which may be readily effected in any suitable way, as for example by first removing the bars 29 and then forcing the container 130 from the core-structure 21-22. After the

container has been stripped from the core-structure 21—22, the core-plates 32 are removed from the handle-portion of the container.

- 5 A container constructed in accordance with my invention is not only highly durable, economical of manufacture, and leak-proof, but also presents a neat and attractive appearance.
- 10 The feature of so forming the mold that the fins of excess material where they join the body of the container, extend in line with the outer surfaces of the container, instead of in line with the top surface of the 15 container considering it in inverted condition, is of advantage, as thereby the molded structure is free of lateral projections at the body portion of the container which, if existent, would obstruct the ready removal of 20 the portion 36 of the mold from the form container.

When desirable the separation of the mold portion 39 from the core with the container thereon, may be effected by supporting the combined core-structure, container and portion 39 upon those portions of the structure 39 which extend laterally beyond the plate to which the core-sections are secured, as will be noted, after the top plate 25 has been removed, and downward pressure applied against the upper surface of the formed container, the latter being inverted, to force the container and core downwardly to free the container from the portion 39, 30 the container afterwards being separated from the core as hereinbefore stated.

While I have illustrated and described a particular construction of apparatus embodying my invention, and described a particular way of utilizing it, I do not wish to be understood as intending to limit my invention thereto, as the same may be variously modified and altered, and the structure used in other ways, without departing 40 from the spirit of the invention.

What I claim as new, and desire to secure by Letters Patent, is:

1. In a mold structure, side walls and a bottom plate having a rabbet in its edge 45 providing a bottom forming surface surrounded by a shoulder, said surface of a

size to project between said side walls with the shoulder spaced therefrom, means to hold the bottom of the rabbet in spaced relation to the edges the walls whereby 55 excess material within said mold may be formed into a flange in a plane offset from the plane of the bottom and overlapping said side walls.

2. A mold structure for molding apertured-handle-equipped containers portions of which present cores about which the material forming the handle portions is molded to form the apertures therein, said cores being removable from the molded handle 60 portions.

3. A mold structure for molding apertured-handle-equipped containers portions of which present handle-portion-forming members separable from the body of the 70 mold and equipped with cores about which the material forming the handle portions is molded to form the apertures therein, said members being removable from the molded container. 75

4. In a mold structure, a bottom plate and a core, said structure presenting ledges extending laterally beyond said core, certain of said ledges containing upwardly open handle forming recesses between their ends. 80

5. In a mold structure, a bottom plate and a core, said structure presenting stepped ledges extending laterally beyond said core, certain of said ledges containing upwardly open handle forming recesses between their 85 ends.

6. In a mold structure, a bottom plate and a core, said structure presenting stepped ledges extending laterally beyond said core and located in different planes, outermost ones of said ledges containing upwardly open handle forming recesses between their 90 ends.

7. In a mold structure, a bottom plate and a core, said structure presenting stepped ledges extending laterally beyond said core and located in different planes, certain of said outermost and innermost ledges containing upwardly open handle forming recesses between their 95 ends.

JOHN M. AHLGREN.
